UNITED STATES PATENT OFFICE.

LUTHER M. DAVIS, OF PORTLAND, OREGON.

RACE-TRACK STARTING-GATE.

No. 825,018.

Specification of Letters Patent.

Patented July 3, 1906.

Application filed October 23, 1905. Serial No. 283,968.

To all whom it may concern:

Be it known that I, LUTHER M. DAVIS, a citizen of the United States, residing at Portland, in the county of Multnomah and State 5 of Oregon, have invented a new and useful Improvement in Race-Track Starting-Gates, of which the following is a specification, reference being had to the drawings, which form a part thereof.

10 My invention relates to improvements in the construction and means for operating race-track starting-gates.

15 The object of my invention is to provide a race-track starting-gate having a series of stalls with automatically-opening gates at one end, having a device for releasing the gates quickly and simultaneously. These objects, as will hereinafter be seen, are accomplished by the novel and useful device 20 which I have discovered. I attain these objects and other practical advantages by the mechanism, construction, combination, and arrangement of parts illustrated in the accompanying drawings, which form a part of 25 this specification.

It is well known that racing animals can seldom be made to start from the same place at the same time because of their naturally high nervous temperament and the inability 30 of men to control them so as to effect a proper and fair start. Especially is this so when there is no means provided to bar their way over the starting-line until a signal may be given and the bar removed to allow their 35 passage. To supply the need for such a bar or gate, I have provided a device which is economical, safe, speedy, and practical and may be set up for use or removed quickly.

In the drawings, Figure 1 is a side elevation 40 of my device, showing a horse in position in one stall and the gates open. Fig. 2 is a front elevation of one stall with gates thereof and part of another stall with surrounding parts of all. Fig. 3 is a plan view 45 of one pair of gates. Fig. 4 is an elevation of part of two gates, showing rings for detent-pin and relative positions. Fig. 5 is an elevation of the detent-pin. Fig. 6 is an elevation showing a coil-spring as another means 50 of opening the gates. Fig. 7 is a perspective view of two stalls provided with my gates, one open and one closed.

Like numerals and letters refer to like parts throughout the views.

55 In my device I provide a series of as many stalls as may be desired, such as the stalls A

and B, Fig. 7. The stalls are formed by frames composed of vertical pipes or rods 8 8' 8" and 9 9' 9", which are connected in pairs by a suitable number of transverse bars 60 10 10 10, as between the pipes 8 and 9, Fig. 7. The vertical pipes 8 8' 8" are provided with tapering lower ends 11 11', Figs. 1, 2, of suitable dimensions to be driven into the ground, and also with collars c c c c, provided with 65 lugs adapted to engage the foot in pressing the standards into the ground. These collars are at a suitable distance from the lower ends of the pipes to prevent them going farther into the ground than desired and to 70 steady them when set up in position. The pairs of vertical pipes 8 9 8' 9' and 8" 9", which with their bars form the sides or frames of the stalls, are held in position by means of the hooked rods 13 13' of suitable length, 75 Figs. 1, 2, 7. These are adapted to engage staples on the upper ends of each pipe, and thus retain the frames at suitable distances apart to form the stalls. At the sides of a series of such stalls and at the front and rear 80 are placed securely in the ground vertical posts C C' of suitable length and dimensions. The outside vertical pipes 8 9 are rigidly secured to the posts C C', respectively, by the straps 17 17', Fig. 7. At the other side of 85 the series of stalls the vertical pipes are secured to the posts C' C' in a similar manner or by means of ropes, or they may be secured to guy-stakes by means of ropes. My object is to provide suitable means for quickly re- 90 leasing the frames at their upper ends so they may quickly and easily be moved to one side. These stalls are each provided with two gates D D', Figs. 1, 2, 7, in front on each vertical frame, and each gate has suitable hinges 95 e e e e.

At the side of each gate at a suitable position on the vertical pipes 9 9' 9 horizontal pulley-arms f f f, Figs. 1, 3, 7, of proper length are fixedly secured to the pipes. These pulley-arms carry at their ends the pulleys g g g. Elastic cords h h h, having a suitable tension, are secured to the vertical pipes at the bases of the pulley-arms and thence passing over the pulleys are secured to the gates D D' at 100 105 the outer edges thereof.

The gate D is provided at a suitable place near its outer edge with a horizontal ring-lock 14 and the gate D' in a similar place with two horizontal ring-locks 14' 14', adapted to receive the ring-lock 14 between them, Figs. 2, 4, 7, and all of the ring-locks are 110

adapted to receive and engage the vertical 5
detent-pins 15 15, Figs. 2, 5, 7. The detent-
pins are suspended vertically in suitable pos-
ition by means of short cords 16 16 at the
lower ends thereof, the upper ends of which
are secured to the transverse cord E. The
operating-cord E is fixedly secured to the
post C' at one end, while the other end passes
over the pulley 17, secured to the top of the
post C and over the pulley 18, secured to the
post C at a suitable height thereon. The
other end of the cord E then extends to some
place convenient to the location of the opera-
tor, so that he may release or draw it taut.
15 The sides of the stalls and the gates are cov-
ered or hung with some suitable fabric
F F F F.

Instead of the elastic cords h h h, which
are adapted to hold the gates open when re-
leased and at the same time permit of their
being closed and secured, a coil-spring G, Fig.
6, may be employed to accomplish a like pur-
pose.

It will be seen that when a series of these
25 stalls, with their gates, are set up in position
on a race-track the gates are closed and
locked by means of the detent-pins. The
horses are driven into the several stalls,
which being of suitable width prevent the
30 animals from turning to the side, crowding
each other, or whirling about, and the sides
being free from projecting parts allow them
to spring forward upon the gates being
opened. This is accomplished by the opera-
35 tion of quickly and firmly drawing taut the
operating-rope E on the signal being given
by the starter. The detent-pins are thereby
drawn upward, at once releasing the gates,
which are automatically swung wide open
40 and retained in that position by means of the
elastic cords h h h. The covered sides and
front prevent the animals from seeing in
those directions, and this in connection with
the gate or bar in front enables the jockey to
45 retain better control of an animal, also to ob-
tain a fair and proper start and to save much
time and nervous energy of both men and
animals. It will be seen, further, that for
races of like or greater distances than a single
50 circuit of a track or course the stalls can be
quickly and easily removed from the track
by displacing the movable hooked rods 13 13',
when each frame can be lifted from the
55 ground and carried to one side ready to be as
quickly set up for the next start with equal
facility and promptness. I prefer to oper-
ate the gates with the elastic opening-cords
h h h; but other means, such as the spring G,
Fig. 6, may also be employed without varia-
60 nance from my invention.

Other changes may also be made by per-
sons skilled in the art other than I have
mentioned without departure from the prin-
ciples of my invention.

I claim—

1. In a race-track starting-gate, the com-
bination of a series of stalls, formed by mov-
able side frames having vertical rods adapted
to be set in the earth; means to secure and
retain the upper ends of the frames at suit-
able distances apart; two automatically-
opening front gates D D' for each stall,
hinged to the frames at the sides; the gate D
having one horizontal ring-lock 14 adapted
to pass between two similar upper and lower
75 ring-locks 14' 14' with which the gate D' is
provided, and said ring-locks being adapted
to receive and engage the vertical detent-pin
15; elastic cords h h of suitable tension se-
cured to the frames at one end, passing over
80 the pulleys g g on arms f f and secured to the
gates at the other end and at a suitable place;
the transverse operating-rope E provided
with vertical cords 16 16 secured to it at
suitable distances and of suitable lengths, at
85 the lower ends of which are secured vertical
detent-pins adapted to engage the ring-locks
of the gates; the vertical guy or supporting
posts C C and C' C'; the operating-rope E be-
ing secured at one side of the series of stalls
90 to the front guy-post C' and passing over
pulleys suitably placed on the front support-
ing-post C to the location of the operator,
and adapted to be loosened or drawn taut for
releasing or raising the detent-pins; and fab-
95 ric covering for the gates and side frames; all
substantially as described.

2. In a race-track starting-gate, the com-
bination of a stall formed by movable side
frames having vertical rods adapted to be
100 set in the earth; means to secure and retain
the upper ends of the frames at suitable dis-
tances apart; two automatically-opening,
horizontal swinging front gates for each
105 stall; the gate D having a horizontal ring-lock
near its outer edge, adapted to pass between
the upper and lower similar ring-locks 14' 14'
on the gate D', said locks being adapted to
receive and engage a vertical detent-pin 15;
110 fabric covering for the gates and frames;
elastic devices to draw and retain the gates
wide open, and means to raise and lower the
detent-pins, all substantially as described.

3. A race-track starting-gate having mov-
able side stall-frames and means to retain
115 them in upright position, two horizontally-
swinging front gates each provided with a
horizontal ring-lock on one gate and two of
like kind on the other relatively above and
below the first, also with means to draw and
120 retain the gates wide open, and further pro-
vided with a vertical detent-pin having
means to raise and lower the same: all sub-
stantially as described.
